GRADING AND SORTING MACHINE

Solomon Guttman, Minneapolis, Minn.

Application December 12, 1931, Serial No. 580,671

8 Claims. (Cl. 209—111)

This invention relates to apparatus controlled by the variance in intensity of an electrical current for the purpose of sorting, selecting or grading articles or material.

5 The invention has extremely wide applicability for the above stated purposes and has special utility for grading and sorting articles through the variance of current intensities effected by subjecting the article to different forms of energy 10 which will variously affect highly responsive media associated with the controlling electrical current and varying the intensity of the current in accordance with characteristics of the article. The medium may be, and preferably is, the photo-electric cell, and rays, such as visible or invisible light, may constitute the source of energy.

It is an object of my invention to provide highly efficient and accurate apparatus for selecting, grading or sorting various articles, controlled by 20 the variance in the intensity of an electrical current, which current is adapted to control electrically operated means for selectively controlling mechanical means to physically separate and/or grade the articles or materials.

25 It is another object to provide apparatus of the class described which is selectively controlled by the characteristics of the material for permitting or restricting passage of energy, such as visible or invisible light, sound waves, heat, radio waves, etc., therethrough.

30 Another and more specific object is to provide apparatus of the class described which is controlled by the intensity of an electrical current which is varied substantially in accordance with the translucency of the article. This phase of the invention is especially applicable to an apparatus 35 for accurately candling, grading and/or sorting eggs.

Still another object is to provide new and improved apparatus controlled by the variance of 40 intensity of an electrical current, for sorting, selecting or grading articles or material and utilizing a photo-electric cell for producing variations in said current and further providing means for subjecting the articles or material to visible 45 or invisible light rays in such manner that the translucency or the ability of the article to reflect or refract light will affect the photo-electric cell and in so doing control electrical mechanism for causing mechanical means to select or grade the 50 article.

The embodiment of the invention illustrated is particularly adapted for automatically candling and sorting eggs in accordance with their condition. It is a fact that improper condition of an

egg, due to decay, heat, cold, humidity, etc., materially changes its light permeability. In the form of my invention illustrated the eggs are successively subjected to a beam of light directed toward a photo-electric cell, which because of its 5 characteristics varies the intensity of an electric current in a relay circuit in accordance with the light intensity impressed upon the cell. The relay or relays selectively control the operation of means for actuating mechanical separating mechanism, which, as shown, includes mechanical means for receiving the eggs successively, cooperating with ejecting means for directing the eggs of the various standards to appropriate receivers.

10 In the specific egg-candling and sorting machine illustrated, the sensitive relay circuit controls a number of electro-magnetic mechanisms, which, in turn, adjust or determine the operating movement of mechanism which receives and carries each egg, after candling, to a predetermined 15 point, depending upon the translucent characteristics of the egg, and which mechanism cooperates with other means for discharging the egg from the carrier to the appropriate one of the several suitable receivers.

20 One form of my invention is illustrated in the attached drawings, wherein like reference characters refer to similar parts throughout the several views, and in which:—

25 Fig. 1 is a horizontal sectional view taken approximately on the line 1—1 of Fig. 2 with the top of the housing removed and showing most of the mechanism in top plan;

30 Fig. 2 is a vertical section taken longitudinally of the machine approximately on the line 2—2 of Fig. 1;

35 Fig. 3 is a vertical cross section taken approximately on the line 3—3 of Fig. 1;

40 Fig. 4 is a detail view in vertical section showing the candling box, the egg turning rollers and showing the direction of the main beam of light when an egg is not positioned operatively for candling;

45 Fig. 5 is a fragmentary horizontal section taken through the wall at the delivery side of the machine and showing in detail the intermittent motion mechanism for operating the egg ejector as well as the paddle wheel for successively feeding the eggs;

50 Fig. 6 is a side elevation of said intermittent motion mechanism;

55 Fig. 7 is an electrical diagram schematically showing the circuits utilized in the form of the invention illustrated in Figs. 1 to 6 inclusive

where the forward type of circuit is employed for the photo-electric cell;

Fig. 8 is an electrical diagram schematically showing modified electrical circuits utilized where the reverse type of circuit for the cell is employed, and

Fig. 9 is a vertical section taken through a modified form of candling box where the photo-electric cell is connected in the reverse circuit schematically shown in Fig. 8.

In the form of my invention illustrated a rectangular frame or housing is provided having the end walls 11 and 12, the side walls 13 and 14 and the horizontal top 15. A main driving shaft 16 is suitably journaled in the end walls 11 and 12, extending longitudinally and horizontally within the upper portion of the frame or housing. This shaft as shown is suitably driven in clock wise direction when viewed from the end 11 of the machine and to this end an electric motor M may be mounted in the bottom of the housing and connected by a belt 17 with a pulley 18 fixed to said shaft 16 for driving the same at suitable speed. A horizontal cross shaft 19 is suitably journaled in bearings provided in side walls 13 and 14 of the housing or frame and rigidly carries a worm gear 20 which is driven by means of a worm 16a carried by the medial portion of shaft 16. Cross shaft 19 revolves clock wise when viewed as in Fig. 2. Most of the working mechanisms of the machine are driven from one or the other of shafts 16 and 19.

A rectangular candling box 21 is supported upon one end of the top 15 of the housing or frame, said box enclosing a smaller rectangular scanning casing 22 in the upper portion thereof. A pair of cooperating spool-shaped or more exactly diabolo-shaped egg-turning rollers 23 are suitably mounted in horizontal alignment within the lower portion of candling box 21, said rollers being affixed to shafts 23a which are suitably journaled in opposite walls of box 21, projecting through the inner wall of the box and provided with aligned driving pulleys 23b which are both driven in the direction indicated by the arrow in Fig. 3 by suitable means such as a crossed belt 24 wrapped around the upper portions of said pulleys and also trained about a larger pulley 25 affixed to the main driving shaft 16. An inclined track or chute comprising, as shown, a pair of rails 26 guides the eggs upon entering the machine to the supporting and turning rollers 23. Directly above the inner end of said track and cooperating with the turning rollers is mounted a paddle wheel 27 fixed to a horizontal shaft 27a which is suitably journaled in the candling box 21 and projects from the inner side thereof rigidly carrying a sprocket 27b. Paddle wheel 27 is driven intermittently through partial revolutions for the purpose of removing an egg from the turning rollers to an inclined delivery chute or track 28 and simultaneously lifting another egg from track 26 onto the turning rollers. The mechanism for intermittently driving paddle wheel 27 is illustrated in detail in Figs. 5 and 6 and comprises an eccentric 29 affixed to cross shaft 19 adjacent the wall 14 of the casing, said eccentric working in a vertical elliptical yoke 30 which is affixed for reciprocating a rod 31 slidably mounted in bearings 32 which may be conveniently attached to wall 14. The opposite end of rod 31 is pivotally connected by a short link 33 with one end of a pawl lever 34 which is journaled upon a stub shaft 35 suitably journaled in bearings affixed to the wall 14 of the casing and projecting

horizontally and laterally of the casing. Pawl lever 34 carries a tooth or pawl 34a which intermittently and progressively rotates a beveled gear 36 by engagement with peripheral teeth 36a carried thereby. A retaining pawl 37 may be mounted on wall 14 above the beveled gear to hold the beveled gear against counter-clockwise movement. Beveled gear 36 is meshed with a smaller beveled gear 38 fixed to a stub shaft 39 which may be journaled in a bracket 39a affixed to the wall 14 and said shaft at its opposite end carries a driving sprocket 40 which is connected for driving the sprocket 27b of the paddle wheel by suitable means such as a chain 41.

The bottom of the scanning casing 22 is provided with a narrow slot 22a affording a light passage (best shown in Figs. 1 and 4) which slot is vertically aligned with the longitudinal center of the space between the egg-turning rollers 23. The length of the slot is preferably somewhat less than the average length of an egg. A main source of light, such as an electrical lamp 42 is positioned at the outer ends of turning rollers 23, midway between the axes of said rollers; and this lamp is covered by means of a casing 43 which is provided with an upwardly inclined, relatively small tubular light passage 43a communicating with the interior and directed between the rollers 23 to a point disposed inwardly of the light slot 22a of the scanning casing, to project a single beam of light as indicated by the dotted line in Fig. 4. A secondary source of light in the form of an electrical lamp 44 is suitably mounted below the bottom of candling box 21 vertically aligned with the space between turning rollers 23 and enclosed by housing 45 which communicates at its upper end with the interior of candling box 21 through a vertical passage 21a in the bottom of said box. A suitable photo-electric cell C is mounted horizontally within scanning casing 22 vertically aligned with the light slot 22a and connected in an electrical circuit hereinafter to be more fully described. A horizontal scanning disk 46 is mounted between photo-electric cell C and light slot 22a, as shown, with its marginal edge just covering said slot and this disk is provided with circumferentially spaced apertures preferably in the form of small circular holes 46a spaced a distance apart substantially equal to the length of light slot 22a. Scanning disk 46 is revolvably mounted in scanning casing 22 and as shown is affixed to the lower end of a vertical shaft 47 which projects through and is journaled in the top of casing 22 and which has affixed to the outer end thereof a bevel gear 47a which is constantly meshed with a bevel gear 48a affixed to one end of a horizontal shaft 48 journaled in a bracket 49. Shaft 48, and consequently scanning disk 46 are constantly driven by suitable means such as an endless belt 50 which surrounds a driving pulley 51 affixed to the main driving shaft 16 which extends longitudinally of the housing of my machine.

The delivery end of the discharge chute or track 28 overhangs a horizontal endless carrier 52 as shown in the form of an apron 52 suitably mounted externally of the wall 14 of the frame and having egg-receiving depressions or recesses 52a spaced longitudinally thereof. Apron 52 may be suitably affixed to a pair of endless chains 53 each of which is trained about a pair of sprockets 54 and 55 respectively, fixed to short shafts 54a and 55a suitably journaled at their inner ends in the wall 14 and as shown journaled at their outer ends in an auxiliary upright frame 56 which is

5 mounted in spaced relation to the side 14 of the main housing or frame. Endless carrier 52 selectively delivers the eggs one at a time to a number of egg-receivers which may be in the form of inclined chutes N, O, P and Q positioned at the outer longitudinal edge of the carrier and extending transversely thereof and slightly overhanging said edge. The endless egg carrier is intermittently driven after candling of the egg 10 to predetermined distances for alignment of the egg with its appropriate egg-receiver or chute, depending upon the characteristics or quality of the egg and suitable mechanism for intermittently driving and varying the travel of said 15 conveyor is provided, as will hereinafter be more fully explained.

Ejecting mechanism is provided for removing the eggs one at a time from conveyor 52 to the appropriate egg receiver or chute N, O, P and Q and as shown includes a horizontal rock shaft 57 journaled in the ends of suitable brackets 58 affixed to the exterior of the wall 14 of the housing, said rock shaft having fixed thereto a series of, as shown, four, normally depending ejector plates 59 each positioned above the conveyor and in front of one of the receivers or chutes. An elongated rocker arm 57a is fixed to rock shaft 57 and the inner end of said arm is connected by a link or pitman 60 with a crank wrist 61a carried by a pinion 61. Pinion 61 is driven by the intermittent motion mechanism previously described for driving paddle wheel 27 which is illustrated in detail in Figs. 5 and 6 and to this end a relatively large driving gear 62 is affixed to stub shaft 39 as shown, being disposed between the beveled gear 38 and the chain sprocket 40, and being in constant mesh with pinion 61. Pinion 61 is journaled on a stub shaft 61b, see Fig. 6, which may be suitably affixed, if desired, to a vertical arm 39b carried by supporting bracket 39a. The ratio of beveled gears 36 and 38 and the ratio of pinion 61 with its driving gear 62 are such that pinion 61 will be driven through a complete revolution for each longitudinal movement of plunger rod 31 in the direction of end 12 of the housing, thereby reciprocating the rocking movement of shaft 57 and consequently the swinging movement of the several ejector plates 59.

The mechanism previously referred to for intermittently driving and varying the travel of conveyor 52 may be of any suitable type provided it can be accurately controlled through the variance in intensity of electrical current in a circuit which includes the photo-electric cell or other energy responsive medium. As shown, shaft 55a for the conveyor 52 is driven by means of a chain 63 which is trained about a driving sprocket 64 and about a suitable sprocket 65 affixed to said shaft. Chain sprocket 64 is affixed to the outer end of a stub shaft 66 suitably journaled in a bearing provided in the wall 14 of the housing. The inner end of conveyor driving shaft 66 has affixed thereto a gear 67 which is in constant mesh with a large driving gear 68 affixed to a cross shaft 69 which may be suitably journaled in the walls 14 and 13 of the housing and which is disposed horizontally some distance below the main driving shaft 16. The large driving gear 68 is intermittently driven through partial revolutions by means of an actuating lever 70 which may be pivoted on the shaft 69 disposed as shown inwardly of large gear 68 and urged against a large actuating cam 71 by suitable means such as a contractile spring 72 (see Figs. 1 and 2). Cam 71 is affixed to cross shaft 19

and revolves clockwise as shown in Fig. 2. Actuating lever 70 carries a pivoted spring actuated pawl 73 which engages a ratchet wheel 74 affixed to shaft 69 for driving large gear 68. It will be apparent that actuating lever 70 has a predetermined throw through its engagement with cam 71 and driving engagement between this lever and ratchet wheel 74 is varied and regulated by mechanism which I will now describe.

An arc shaped ratchet guard 75 is mounted externally and eccentrically of ratchet 74 and has a free end which is disposed beneath pawl 73 covering a number of the teeth of ratchet 74 and when moved counter clockwise as shown in Fig. 2, raising pawl 73 and preventing said pawl from engaging the ratchet until actuating lever 70 has moved through a predetermined angulation. Ratchet guard 75 may be affixed to a radial arm 16 which is pivotally mounted upon shaft 69 and the position of said arm and guard consequently determines the portion of the throw or movement of actuating lever 70 which directly effects the driving of ratchet 74 and with it the large gear 68.

Suitable means are illustrated in the accompanying drawings whereby the position of ratchet guard 75 may be regulated although it will, of course, be understood that other means may be substituted if desired. As shown, said regulating means includes a sector 16a rigidly attached to the radial arm 16 and urged upwardly by suitable means such as a contractile spring 77. Sector 16a is normally held downwardly in the position shown in Fig. 2 by means of a small lever 78 which may be pivoted to the wall 14 of the housing and which engages a horizontal pin 76b mounted at the lower end of sector 16a the opposite end of said lever being controlled by means of a small cam 79 which is affixed to a horizontal stub shaft 80 suitably journaled in the lower part of wall 14 (see Figs. 2 and 3). Shaft 80 and cam 79 are driven from the main cross shaft 19 by means of a chain 81 trained about suitable sprockets 80a and 19a fixed to the respective shafts and said sprockets are of the same diameter in order that the shafts 19 and 80 will be driven at the same speed. Selective positioning of sector 16a and consequently guard 75 is directly controlled by the abutment of an arm 82 with the lower end of an automatically adjustable sector 83. Arm 82 is pivoted to one of the faces of sector 16a on substantially a vertical axis and is urged by a leaf spring 82a toward the wall 14 of the housing. Arm 82 has a depending angular extension 82b which rides against a profile cam 84 affixed to the inner end of stub shaft 80, said cam controlling the swinging of arm 82 to release it from abutment engagement with the lower end of sector 83 at a predetermined time in the cycle of operation of the machine.

Sector 83 is urged downwardly by suitable means such as a coil spring 85 and the position of said sector is controlled by means of a series of, as shown three, electromagnetically controlled levers 86 of the bell crank type (see Fig. 3) having short horizontal ends 86a, which are actuated by short horizontal levers or armatures 87 suitably fulcrumed and controlled by electromagnetic coils hereafter to be fully explained. Sector 83 is connected by a radial arm 83a with a shaft 88 and said radial arm has an extension at the opposite side of shaft 88 which is engaged by the turned upper ends of magnetically controlled levers 86, the points of engagement of said levers being positioned different radial distances from

shaft 88 and assuming the throw of the levers to be equal, effecting different movements of sector 83. Before sector 83 is set it normally rests upon a stop pin 89 supported from the wall 14. Sector 83 at its outer edge is provided with two arcuate sets of ratchet teeth 83b and 83c respectively, the inner set, 83b of which are directed downwardly and are engageable with a retaining pawl 90 to limit the downward movement of the sector when it has been regulated by levers 86. Pawl 90 is urged against teeth 83b by means of a leaf spring 90a.

A double action retaining member 91 is pivotally mounted adjacent its lower end on a pin 91c which may be conveniently affixed to the wall 14 of the housing and which is positioned substantially centrally between the arcuate paths of movement of sectors 16a and 83. Retaining element 91 at its lower end is provided with a pair of outwardly and downwardly projecting engagement teeth one of which is adapted to engage with the outer series of ratchet teeth 83c carried by segment 83 when element 91 is positioned as shown in Fig. 2. The other retaining tooth of element 91 is adapted to engage with upwardly directed ratchet teeth carried by sector 16a when element 91 is swung to cause said last mentioned retaining tooth to move downwardly and in a left hand direction as viewed in Fig. 2. Element 91 has an upwardly extending arm 91a which is urged against an actuating cam 92 fixed to cross shaft 19. Retaining element 91 carries a tooth equipped arm 91b extending from the right hand side thereof as viewed in Fig. 2, the tooth of which is adapted to engage and retract retaining pawl 90 from engagement with the inner series of ratchet teeth 83b of sector 83, at a predetermined point in the cycle of operation of the machine.

The three levers 86 which selectively control the position of sector 83 are operated by means of three electromagnets X, Y and Z which may be conveniently positioned on a horizontal shelf 93 mounted in the main frame or housing and disposed below the short levers 87. Levers 87 act as armatures, the ends thereof toward wall 13 of the housing being attracted when their respective electromagnets X, Y and Z are energized and swinging downwardly to in turn swing levers 86. Electromagnets X, Y and Z are selectively energized as shown in Figs. 1 and 7 through the contacts of a suitable relay mechanism comprising an electromagnetic coil 94 having mounted therein a plunger 95 which is connected by a link or other means with a movable contact or arm 96 normally positioned out of engagement with the respective contacts x, y, z and a which control the three electromagnets X, Y and Z; and mounted to selectively wipe said contacts in accordance with the intensity of the current flowing through electromagnetic coil 94. Movable contact 96 may be urged in one direction by suitable means such as a coil spring 96a. Suitable circuits for selectively energizing electromagnets X, Y and Z are schematically shown in Fig. 7, said circuits having in common a suitable source of electrical current, such as the battery 97.

A suitable electrical controlling system which includes the photo-electric cell C is provided for varying the electromagnetic force exerted by coil 94 of the relay mechanism in accordance with the light permeability and consequently the quality of each egg or other article scanned or candled by the device.

In Figs. 1 to 3 inclusive the machine is shown

as equipped with a candling box, scanning casing and sources of light for a system or photo-electric circuit of the forward type, where the intensity of the current in the output circuit increases in accordance with the increase of light to which the photo-electric cell C is subjected. A suitable forward circuit for energizing relay coil 94 is schematically shown in Fig. 7, said circuit including three stages of amplification effected as shown by means of conventional thermionic amplifiers which must be of a type for applying D. C. As shown, separate sources of filament supply current are provided by A-batteries for each thermionic tube and a single large B-battery may be tapped at different points as schematically illustrated to provide plate current and grid bias.

Referring again to the selective switch for controlling the three electromagnets X, Y and Z, it will be noted that the contacts x, y, z and a are arranged circumferentially in an arc concentric with the pivot of movable contact 96. It will further be noted that contact a (see Fig. 7) is spaced from contact z approximately twice the distance between contacts x and y and contacts y and z. The normal position of movable contact 96 when the lights 44 and 42 are illuminated and no egg is in the candling box is, as shown in Fig. 7, midway between contacts z and a, the light intensity affecting the cell at that time being slightly below maximum. Contact a, it will be noted, is electrically connected with electromagnet Z which controls the regulating mechanism for operating the conveyor 52 to direct an egg to the second grade receiver P.

When contact x, shown in Fig. 7, is engaged, electromagnet X is energized, controlling the delivery of fourth grade eggs, to receiver N. Engagement of contact y controls energization of electromagnet Y and delivery of third grade eggs to receiver O. When contact z is engaged electromagnet Z is energized controlling delivery of second grade eggs to receiver P. Movable contact 96 is positioned to engage fixed contact z when a second grade egg which is somewhat less translucent than the first grade eggs is scanned or when an egg having small or slight spots therein is interposed between the source of light and the photo-electric cell C. The normal or illustrated position of movable contact 96 does not change the position of regulating mechanism and the conveyor is operated for delivering first grade eggs to receiver Q. Engagement of the upper contact a energizes electromagnet Z and controls the delivery, to receiver P, of a second grade egg of the type where air cells are present within the shell due to drying or shrinkage of the contents. The above mentioned type of egg is quite common and is classed, commercially, as a "second" grade egg. This type of egg when scanned causes the impression of a maximum amount of light on photo-electric cell C raising the movable contact 96 above its normal position into engagement with contact a.

With a forward type of photo-electric cell circuit it is desirable to normally maintain the regulating sector 83 in the lowered position against stop pin 89 for effecting a maximum travel of grading conveyor 52 whereby the best conditioned egg will be removed to its receiver Q. To this end the auxiliary light 44 is positioned below candling box 21 throwing a maximum amount of light upon the photo-electric cell C at such times as the machine is empty or in transitional periods between the removal of an egg from the turning roller 23 and the supply of the next egg.

In Fig. 8 a reverse type of photo-electric circuit is shown for variably controlling the energization of the magnetic coil 94 of the relay, wherein the intensity of the electrical current and consequently the force exerted by the coil of the relay is decreased in accordance with the increase of light transmitted to the photo-electric cell. The normal or starting position of the movable contact 96 of the relay must be reversed in this reverse circuit and the position of contacts *x*, *y* and *z* which control the circuits through electromagnets *X*, *Y* and *Z* respectively must also be reversed. It is also desirable where the reverse photo-electric circuit or system is used to somewhat modify the locations and functions of the sources of light in the candling box and scanning casing.

Fig. 9 shows a suitable construction of candling box, scanning casing and sources of light for use in said reverse circuit. In such construction the main source of light or lamp 100 is mounted below candling box 21 vertically aligned with the space between turning rollers 23 and with photo-electric cell C. A small auxiliary light 101 is disposed in the scanning casing between scanning disk 46 and photo-electric cell C and has a constant effect on the cell. The cell is thus subjected to maximum light before an egg is positioned on the turning rollers and during the transitional period when an egg is being removed to the grading conveyor 52 and before the next egg is centered upon the rollers. At such time the movable contact 96 of the relay is positioned as shown in Fig. 8.

The auxiliary light 101 is provided, when the reverse circuit is utilized, mainly for the purpose of producing a minimum limit on the amount of light directed against the photo-electric cell. This prevents an excessive output in the intensity of the current in the controlling circuit. The auxiliary light also has the effect of increasing at all times the amount of light directed against the cell which has been found by me to be of advantage if a reverse type photo-electric cell is utilized.

Operation

In the form of the invention illustrated the eggs are directed by declined track 26 to the paddle wheel 27, which is intermittently driven through partial revolutions. Paddle wheel 27 in each intermittent movement lifts one of the eggs to the scanning position upon the turning rollers 23. Rollers 23 are constantly driven, as is scanning disk 46, and the egg while it is supported upon said rollers and before it is removed therefrom is turned through at least one complete revolution.

Assuming the candling and scanning mechanism to be constructed as illustrated in Figs. 1 to 4 inclusive and assuming that the forward type of photo-electric cell circuit is used, next to the maximum intensity of light is impressed upon the photo-electric cell C by auxiliary light 44, before the first egg enters the candling position. The intensity of the current in the output circuit of the amplifier is then maximum, causing the movable contact 96 of the relay device to be held in the neutral or first grade egg position, schematically shown in Fig. 7. Regulating sector 83 is then held in the neutral position by means of springs 85 against the stop pin 89.

The egg upon rollers 23 will be candled or illuminated chiefly by the main source of light 42, the intense beam of said light striking the bottom of the egg and being diffused and diverted

to more or less illuminate the entire egg. The diffused light rays pass upwardly through the egg, through the slot 22a at the bottom of scanning casing 22 and through scanning disk 46 and are impressed upon the cell. The cooperation of the scanning disk 46 having the small circumferentially spaced apertures adjacent its periphery and the turning rollers produces an efficient scanning or candling of the entire egg. If the egg being candled is a first grade egg having no opaque spots throughout, substantially the same intensity of light is impressed upon the cell as was present before the egg was introduced into the candling box. This is due to the influence of the main source of light 42 which did not affect the photo-electric cell before the egg was moved into scanning position.

Assuming that the egg just scanned possesses bad characteristics and is No. 4 grade, the intensity of light directed against cell C will be greatly reduced, effecting a decrease in the intensity of current in the controlling circuit and consequently reducing the magnetic effect exerted by coil 94 of the relay device, whereby the movable contact 96 will engage fixed contact *x* closing the circuit through electromagnet *X*, which operates the left hand controlling lever 86 swinging the regulating sector 83 to the extreme upward position shown in Fig. 2 of the drawings. The various regulating and actuating elements of the machine are so synchronized that the large actuating cam 71, the small cam 92, for actuating the double action retaining element 91, the small cam 79 for releasing the sector 76a and the profile cam 84 for permitting disengagement of the stop arm 82 with the lower end of sector 83 are all positioned as shown in Fig. 2 just after an egg of No. 4 grade has been scanned. At this step of the operation the regulating sector 83 has been locked against upward swinging movement by the engagement of the right hand tooth of double action retaining element 91 with one of the teeth 83c of the sector and against downward swinging movement by the engagement of retaining pawl 90 with one of the inner series of teeth 83b carried by the sector. After the proper positioning and locking of regulating sector 83, paddle wheel 27 in the candling box is again driven by the intermittent driving mechanism illustrated in Figs. 5 and 6 through a partial revolution discharging the scanned egg upon one of the depressed portions 52a of conveyor 52 and simultaneously lifting a second egg from track 26 onto the scanning rollers 23.

Simultaneously, drive controlling sector 76a of the regulating mechanism is released after the high point of the small cam 80 disengages the right hand end of the small retaining lever 78. Sector 76a swings upwardly, urged by coil spring 77 until the retaining arm 82 strikes the lower end of regulating sector 83. Drive controlling sector 76a carries with it the regulating ratchet guard 75, which, in the upward swinging action of sector 76a, engages and releases pawl 73. Double action retaining element 91 is then moved counter-clockwise by engagement of its shank 91a with the high point of the small cam 92 fixed to cross shaft 19 to cause the left hand tooth of said retaining element to engage the upwardly extending teeth of sector 76a, said engagement and consequent locking taking place before the right hand tooth of retaining element 91 has completely disengaged the teeth 83c of regulating sector 83. Further swinging movement of retaining element 91 causes the complete disengagement

ment of the teeth 83c of regulating sector 83 and also causes the hook tooth 91b to momentarily release the retaining pawl 90 from engagement with the inner series of teeth 83c carried by the regulating sector 83, releasing sector 83 which is then returned to neutral position by the spring 85. Immediately after release of said sector, hook tooth 91b slips past the end of retaining pawl 90. Just prior to the release and return of retaining sector 83 the profile cam 84 engages the depending end 82b of stop arm 82 causing said stop arm to swing out of the return path of sector 83.

Drive controlling sector 16a and ratchet guard 75 are now positioned and locked as controlled by the scanning of a No. 4 grade egg and at this time the large actuating cam 71 has moved through approximately one-half a revolution from the position shown in Fig. 2 and engages throw lever 70 swinging the same to the left. When lever 70 has swing a sufficient distance to permit the pawl 73 to disengage the end of the arcuate tooth guard 75, ratchet 74 will be engaged by said pawl and the driving gear 68 will be driven through a partial revolution thereby driving the gear 67 a predetermined number of revolutions, which in turn drives the conveyor 52, positioning the No. 4 grade egg directly in front of its appropriate receiver or chute N. Lever 70 is returned to normal position by spring 72. Drive controlling sector 30 16a is slowly returned to its neutral position by the swinging of the small lever 78 which engages the pin 76b at the lower end of sector 16a, and the left hand end of which is swung downwardly by the small cam 79.

Immediately after conveyor 52 has been driven the predetermined distance ejector plates 59 are swung rearwardly by means of the intermittent motion mechanism illustrated in Figs. 5 and 6, discharging the No. 4 grade egg from the conveyor to the chute or receiver N. Simultaneously paddle wheel 27 is again moved through a partial revolution removing a second egg from the turning rollers 23 to the conveyor and also at the same time lifting a third egg into scanning position upon rollers 23.

The operation is the same for second and third grades of eggs scanned, the variances in the intensity of the current in the output of the amplifier effecting the relay device and causing the appropriate electromagnet X, Y or Z as the case may be to swing its corresponding lever 86 for properly positioning regulating sector 83. When a first grade egg is scanned, regulating sector 83 remains in the neutral position and is locked therein at that time abutting the stop arm 82 of drive controlling sector 16a, the other operations of the regulating and conveyor driving mechanism being as above related.

When a second grade egg of the type where air cells are present within the shell due to drying or shrinkage of the contents, is scanned, a slightly greater intensity of light is impressed upon the photo-electric cell than in the case of a first grade egg. This increased intensity of light with the forward circuit effects an increased intensity in the current of the output of the system, swinging movable contact 96 into engagement with the contact a which effects the energization of electromagnet Z (as does engagement of contact z) and the said egg having the air cells is delivered automatically to the second grade receiver P.

The operation of the machine is similar to that above described when the reverse type of photo-electric cell circuit is utilized, as is schematically shown in Fig. 8 and when the candling and scan-

ning mechanism shown in Fig. 9 is employed. It will be noted, however, that in the diagram for the reverse type of photo-electric cell circuit I have not provided means in the selective switch for grading an egg which has air cells due to shrinkage of its contents, although it will of course be obvious that the same may be provided for.

It will be noticed that the levers 86 which control the positioning of regulating sector 83 and the controlling circuits are so arranged that the lever producing the greatest swinging variance of the sector, to wit, the lever nearest the fulcrum of the sector, is controlled in the forward circuit by a relatively small intensity of the current passing through electromagnetic coil 94 of the relay. Thus the effects of the other levers are successively cut out and if any opaque spots are present in the egg affecting the intensity of light during scanning the grade is determined from the darkest spots of the egg rather than from the lightest spots of the egg, except in the instance where an egg of the type having air cells is scanned.

While the embodiment of the invention illustrated is primarily for the purpose of automatically, quickly and efficiently candling eggs, it will be apparent that operating and selecting mechanism controlled by a variance in the intensity of an electric current may be employed for grading or sorting various different articles or materials in accordance with their characteristics, including visible or invisible light permeability, reflection, refraction, and numerous other characteristics all within the scope of my invention.

It will also be understood that in a machine or apparatus for selecting or grading material which is controlled by the translucency or light permeability of the article or material, I am not limited to the specific regulating and physical selecting or separating means illustrated and described herein.

In the claims the words "radiant energy" are used in the broad sense to include energy, such as visible or invisible light, heat, radio activity and radio waves.

In the claims the expression "indicating the grade" is used broadly to include the physical separation of the articles tested, the marking or otherwise identifying of the articles or the indicating by instruments, signals or the like.

The terms "regulating element" and "regulated element" refer broadly to elements capable of performing the functions of applicant's regulating sector 83 and regulated sector 16a, respectively.

What is claimed is:—

1. In grading or sorting apparatus, means for successively testing a series of articles whereby characteristics of said articles will vary the intensity of an electrical current, a series of receivers for articles of different grades, a conveyor movable variable distances for carrying an article to any one of said several receivers, means for positioning an article upon said conveyor after it has been tested, means for driving said conveyor, actuating means having a predetermined movement, means for connecting said actuating means with said conveyor driving means in a plurality of different positions corresponding to the number of said receivers whereby said conveyor will be driven a different distance to deliver to each receiver and relay mechanism responsive to the intensity of said electrical current.

cal current for selectively controlling said regulating means.

2. In grading or sorting apparatus, a testing chamber, means associated with said chamber for testing an article positioned therein whereby characteristics of said article will determine the intensity of an electrical current, means for intermittently introducing articles, one at a time, into said chamber, an endless conveyor positioned at one end of said chamber, means for removing an article after testing from said chamber to said conveyor, a series of receivers for articles of different grades, all having communication with said conveyor, a driving member for said conveyor, an actuating element, means for moving said actuating element through a predetermined course, means for connecting said actuating element with said driving member in a plurality of different positions corresponding to the number of said receivers whereby said conveyor will be driven a different distance to deliver to each receiver and regulating means for selectively determining the position of connection of said actuating element, said regulating means including electro-magnetic mechanism selectively controlled by the intensity of the electrical current in the output of said testing means.

3. In grading or sorting apparatus, article testing means including a photo-electric cell and a circuit including said cell and having an output wherein the intensity of current varies in accordance with the characteristics of articles tested, a plurality of article receivers, article directing means adapted to receive articles from said testing means and adapted to direct articles to any one of said several receivers, a regulating element, the position of which is controlled by said testing means, a regulated element normally disconnected from said regulating element, means for periodically urging said regulated element in a direction where it will engage and be set in any one of several predetermined positions in accordance with the position of said regulating element and means associated with said regulated element for selectively controlling the operation of said article directing means.

4. In grading or sorting apparatus, article testing means whereby characteristics of an article will vary the intensity of an electrical current, a plurality of article receivers, article directing means adapted to receive articles from said testing means and adapted to direct articles to any one of said several receivers, an adjustable regulating element, electro-magnetic means selectively controlled by said testing means and operative to adjust said regulating element, means for momentarily locking said element in an adjusted position after an article has been tested, a regulated element, means for moving said regulated element into abutment with said regulating element immediately after said regulating element is locked in adjusted position, means for locking said regulated element after it has been adjusted by abutment with said regulating element, means for immediately thereafter releasing engagement between said regulating and regulated elements and means associated with said regulated element

for selectively controlling the operation of said article directing means.

5. In apparatus for grading or sorting eggs, a testing chamber having therein a source of light, an egg support and a photo-electric cell circuit for varying the intensity of an electrical current in accordance with the translucency of eggs tested, a plurality of electrical circuits each adapted to control the selection of one grade of eggs, one of said circuits controlling the selection of second grade eggs, a selective relay switch controlled by the output of said photo-electric cell circuit, said switch including a movable contact and a series of fixed contacts, one of said contacts being engaged by said movable contact when an egg having somewhat less translucency than a first grade egg is tested, another of said contacts being engaged by said movable contact when an egg having greater translucency than a first grade egg is tested, both of said specifically mentioned contacts being connected in the circuit for controlling the selection of second grade eggs.

6. In grading or sorting apparatus, means for testing an article whereby characteristics of said article will vary the intensity of an electrical current, mechanical mechanism for indicating the respective grades of articles tested, means for subjecting only a portion of an article at a time to said testing means, means for moving an article being tested to successively subject portions of said article to said testing means, a regulator for said grade indicating mechanism and a series of movable elements each of a different sensitivity controlled selectively by the variance in intensity of the current of said testing means, each of said elements having a different predetermined regulating movement and consequently having a different predetermined regulating effect on said regulator.

7. The structure set forth in claim 6, and means for restraining movement of said regulator in one direction during said testing period.

8. In grading or sorting apparatus, a testing chamber, means associated with said chamber for testing an article positioned therein whereby characteristics of said article will determine the intensity of an electrical current, means for intermittently introducing articles, one at a time, into said chamber, a carrier for receiving articles, one at a time, after testing, a series of receivers for articles of different grades, all connectable with said carrier in different predetermined positions of said carrier, an actuating element, means for moving said actuating element through a predetermined course, a driving member for said carrier, means for connecting said actuating element with said driving member in a plurality of different predetermined positions corresponding to the number of said receivers whereby said carrier will be driven a different distance to deliver to each of the several receivers and regulating means for selectively determining the position of connection of said actuating element, said regulating means being responsive to the intensity of electrical current.

SOLOMON GUTTMAN.
